UNITED STATES PATENT OFFICE.

JOHN A. HOOPER, OF SOUTHARD, PENNSYLVANIA.

STAND-PIPE CONNECTION FOR OIL-WELLS.

SPECIFICATION forming part of Letters Patent No. 772,804, dated October 18, 1904.

Application filed March 24, 1904. Serial No. 199,723. (No model.)

To all whom it may concern:

Be it known that I, JOHN A. HOOPER, a citizen of the United States, residing at Southard, in the county of McKean and State of Pennsylvania, have invented new and useful Improvements in Stand-Pipe Connections for Oil-WellS, of which the following is a specification.

My invention pertains to stand-pipe connections for oil-wells, and has relation to an improved means to prevent the bending and breaking of the stand-pipe or tubing through the action of the polish-rod and the movement of the walking-beam.

In the usual form of devices used for pumping oil from oil-wells the polish-rod is connected to one end of the walking-beam and passes through the stand-pipe and tubing and is connected with the suction-rod in the well.

Owing to the fact that the end of the walking-beam describes the segment of a circle, the upper end of the polish-rod has a horizontal vibration, and it is found in such constructions the vibration is transmitted to the stand-pipe and the tubes, and owing to the rigid connection between the stand-pipe and the tubes either the stand-pipe or the tubes are frequently broken above the casing-head and in some instances below the casing-head.

The object of my present invention is to provide means to prevent the bending and breaking of the stand-pipe or the tubes.

In the accompanying drawings, Figure 1 is a side elevation of my invention, showing it in connection with a walking-beam. Fig. 2 is a detached longitudinal sectional view of my improved flexible connection. Fig. 3 is a detached view of one of the clamps for holding the flexible connection to the stand-pipe and tube.

Referring now to the drawings, 1 indicates the ordinary walking-beam, which has one end connected with any suitable means 2 for the purpose of reciprocating it, and 3 is the casing-head of an oil-well. Projecting from the casing-head is a portion of the tubing 4, and 5 is the stand-pipe, provided with the usual stuffing-box 6 at its upper end. Passing through the stand-pipe 5 and the tubing 4 and connected with the sucker-rod in the well (not

here shown, as they are so well understood,) is the usual polish-rod 7. This polish-rod is suitably connected in the usual and well-known manner to the free end 8 of the walking-beam 1.

Instead of connecting the stand-pipe 5 rigidly with the projecting end of the tubing 4, in which rigid connection it necessarily follows that there is a vibration of the stand-pipe and tube 4, owing to the fact that the free end of the walking-beam describes the segment of a circle, I provide a flexible connection 9 between the lower end of the stand-pipe 5 and the projecting end of the tube 4. This flexible connection may consist of rubber, canvas, or the ordinary hose tubing and, as here shown, is a section of a flexible tube, having its respective ends clamped to the adjacent ends of the stand-pipe and the tube through the medium of clamps 10. From the foregoing it will be readily observed that this flexible connection permits the stand-pipe to vibrate independent of the tube 4, thus preventing a bending of either the tube or the stand-pipe and also preventing a breaking of either of the parts. Furthermore, this flexible connection relieves a great deal of friction and wear, and hence produces a construction which is easier in its operation.

Owing to the fact that the stand-pipe 5 vibrates, it is necessary to provide for this vibration in some manner in the connection 11, through which the oil flows from the stand-pipe to the oil-tank 12. This is accomplished by making the connection 11 either of a flexible tube or having its ends resting loosely upon the oil-tank and permitted to move back and forth.

Since the oil is drawn from the well by the sucking or pumping apparatus through the stand-pipe 5, it is necessary that the flexible joint should be a tight one, and in the construction here shown a perfectly tight flexible joint is provided.

Having thus described my invention, what I claim, and desire to secure by Letters Patent, is—

1. In a device of the character described, the combination with an oil-well tube, of a stand-pipe separate from the oil-well tube, a

flexible connection connecting the adjacent ends of the stand-pipe and the oil-well tube and holding them out of engagement, a walking-beam, and a polish-rod passing through the stand-pipe and connected with the pumping apparatus, substantially as described.

2. In a device of the character described, the combination with an oil-well tube, of a stand-pipe, a flexible connection between the tube and the pipe, a walking-beam, a polish-rod passing through the stand-pipe and connected at one end with the walking-beam, and at its opposite end with the pumping apparatus, and an oil-exit connected with the stand-pipe at a point above its flexible connection and connected with a receiving-tank, the said oil-exit being so constructed as to permit a vibration of the stand-pipe, substantially as described.

3. In a device of the character described, the combination with an oil-well tube, of a stand-pipe, a flexible tube passing over the tube and the stand-pipe, clamps passing around the flexible tube and clamping it to the well-tube and the stand-pipe, a walking-beam, a polish-rod having its upper end secured to the walking-beam and passing through the stand-pipe, the flexible connection, the well-tube, and having at its lower end the pumping apparatus, and an oil-exit connected with the stand-pipe at a point above the flexible tube.

In testimony whereof I have hereunto set my hand in the presence of two subscribing witnesses.

JOHN A. HOOPER.
